[57] CLAIM

The ornamental design for a combined heel and sole for
women's shoes, as shown and described.

DESCRIPTION

FIG. 1 is a left side elevational view of a combined heel
and sole for women's shoes showing my new design;
FIG. 2 is a right side elevational view thereof;
FIG. 3 is a bottom plan view thereof;
FIG. 4 is a front elevational view thereof;
FIG. 5 is a rear elevational view thereof;
FIG. 6 is a top plan view thereof;
FIG. 7 is a left side elevational view of another embodi-
ment of my new design of FIGS. 1-6;
FIG. 8 is a right side elevational view thereof;
FIG. 9 is a bottom plan view thereof;
FIG. 10 is a front elevational view thereof;
FIG. 11 is a rear elevational view thereof;
FIG. 12 is a top plan view thereof.
